UNITED STATES PATENT OFFICE.

MILTON H. HART, OF BROOKLYN, NEW YORK.

SWIVEL-COUPING.

No. 918,542.

Specification of Letters Patent.

Patented April 20, 1909.

Application filed April 9, 1908. Serial No. 426,135.

To all whom it may concern:

Be it known that I, MILTON H. HART, a citizen of the United States, and a resident of the borough of Brooklyn, county of Kings, and State of New York, have invented a certain new and useful Swivel - Coupling, of which the following is a specification.

This invention relates to swivel couplings, and the objects of the invention are to provide a swivel coupling, particularly adapted for use in hose nozzles which shall be watertight under great pressure and which shall be easy to manipulate.

Further objects of the invention will be hereinafter mentioned and pointed out in the claims.

In the drawings: Figure 1 is a front view partly in section and with parts broken away of a nozzle with couplings constructed according to my invention; Fig. 2 is a view of the complete nozzle; and Fig. 3 is a detail view of a washer.

Referring to the drawings the coupling member 1 which permits of the nozzle being turned in a horizontal plane, consists of an exterior sleeve 4 provided with a thread 5 for attachment to the end of a hose or the like, and with an internal annular flange 6 adjacent to the thread 5. The upper face of the flange 6 is provided with an annular groove 7, the function of which will appear. The coupling member 4 is also provided with internal threads 8 and with lateral apertures 10 and 11 intersecting these threads and shown as countersunk for the reception of screws 12 and 13 respectively. Within the exterior sleeve 4 is an interior sleeve 14 having a thread 15 at its outer end for engagement with a T-connection 50 and provided with an external annular flange 16, the outer face of which has a rotary fit within the body of the coupling 4. A collar 17 is provided with an outer thread 18 adapted to engage with the thread 8 in the sleeve 4 and having its inner face adapted to rotary fit on the outer surface of the interior sleeve 14. A cap 19 is provided with an external thread 20 adapted to engage with the threads 8 on the sleeve 4 and with a flange 21 fitting over the edge of the sleeve 4. The upper and lower faces of the flange 16 and the lower face of the collar 17 are provided with annular grooves 22 and 23 respectively, these being similar to the grooves 7 in the flange 6. The adjacent faces of the collar 17 and cap 19 are spaced apart to form a recess for a packing

24. Antifriction balls 25 are placed between the annular grooves in the flanges 6 and 16 and the collar 17 to provide for the easy rotation of the exterior sleeve 4 and the interior sleeve 14 upon each other.

To prevent the water working itself upwardly between the exterior sleeve 4 and the interior sleeve 14 I preferably provide a washer 251 which is secured to the end of the inner sleeve 14 by means of a metal ring 26 through which suitable screws 27 are fastened to the end of the inner sleeve 14 which is preferably made flush with the bottom of the flange 6 so that the washer 251 is adapted to overlap the joint made by the end of the inner sleeve 14 and the flange 6. It will also be noted that the metal ring 26 is adapted to overlap the joint made by the inner sleeve 14 and the flange 6, although the metal ring 26 preferably does not extend to the full diameter of the outer sleeve, for in this manner it will be seen that the water under pressure which is moving in the direction of the arrow, will be permitted to force itself against the outer surface of the washer 251 and with the increasing in pressure will hold the washer more firm against the bottom of the flange 6 and so prevent the possibility of any water ever leaking upward between the inner sleeve 14 and the outer sleeve 4.

I have shown this swivel coupling as forming a part of a hose nozzle comprising a T-connection 50, secured to the swivel coupling by means of screw threads 15, and provided at its ends with swinging elbows 51 to the outer ends of which are secured the converging pipes 52 leading to a Y-connection, as shown in Fig. 2. Between the T-connection 50 of these elbows 51 are suitable joints 53 formed by flanges 53 on the T-connections, each such flange provided with an inner flange 54 and an outer flange 55 inclosing between them packing material 62. The elbows 51 are provided with flanges 56 and 58 and with inner flanges 57 bearing against the corresponding portions of the T-connection 50. Collars 61 screw threaded at 60 unites the elbows to the T-connection 50. To prevent binding of the elbow joints due to high water pressure a rod 65 is provided extending from one elbow through the T-connection to and through the other elbow, and passing through suitable bearings 66 in said elbows and provided at its end with suitable nuts 67.

What I claim is:

1. A swivel joint comprising an exterior

sleeve having an internal annular flange, an inner sleeve having an external annular flange, a collar having detachable engagement within said exterior sleeve for retaining
5 said interior sleeve in position, means for retaining said collar within said exterior sleeve, the flange on said interior sleeve being embraced between the flange on said exterior sleeve and said collar, a washer secured to the end of said inner sleeve and overlapping the end of the annular flange on said exterior sleeve, and means for holding said washer in place.

10 2. A swivel joint comprising an exterior sleeve having an internal annular flange, an inner sleeve having an external annular flange, a collar having detachable engagement within said exterior sleeve for retaining

said interior sleeve in position, means for retaining said collar within said exterior sleeve, 20 the flange on said interior sleeve being embraced between the flange on said exterior sleeve and said collar, a washer secured to the end of said inner sleeve and overlapping the end of the annular flange on said exterior 25 sleeve, and means for holding said washer in place, said washer holding means also overlapping the end of the annular flange on said exterior sleeve.

In testimony whereof I have signed this 30 specification in the presence of two subscribing witnesses.

MILTON H. HART.
